BATHING HOLDER FOR INFANTS

Luella E. Moore, Myrtle Creek, Oreg.

Application December 12, 1955, Serial No. 39,292

Term of patent 14 years

(Cl. D4—4)

Figure 1 is a perspective view of the top side of a bathing holder for infants embodying my new design;

I claim:

The ornamental design for a bathing holder for infants, as shown.
